United States Patent Office

Des. 183,351
Patented Aug. 12, 1958

183,351

CHRISTMAS ORNAMENT OR SIMILAR ARTICLE

Heranoush Keljik, Evanston, Ill.

Application August 1, 1957, Serial No. 47,183

Term of patent 7 years

(Cl. D29—1)

Fig. 1 is a side elevational view of a Christmas ornament or similar article, showing my new design;

Fig. 2 is a top plan view; and

Fig. 3 is a bottom plan view thereof.

I claim:

The ornamental design for a Christmas ornament or similar article, as shown.
